(57) **CLAIM**

The ornamental design for a pipe, as shown and described.

DESCRIPTION

FIG. 1 is a top, front, left perspective view of a pipe, showing our new design;

FIG. 2 is a top, front, right perspective view thereof;

FIG. 3 is a front elevation view thereof, where the rear elevation view is identical thereto;

FIG. 4 is a top plan view thereof, where the bottom plan view is identical thereto;

FIG. 5 is a left side elevation view thereof, where the right side elevation view is identical thereto; and,

FIG. 6 is an enlarged front elevation view as indicated in FIG. 3, it being understood that the slit shown in FIG. 6 is representative of the slits that are evenly spaced to each other around the entire circumference of the pipe.

The portions depicted in broken lines of even length depict portions of the pipe that form no part of the claimed design. The portions depicted in broken lines of uneven length shown in FIGS. 1, 2, and 5 define the unclaimed boundary of the claimed design.

The portions depicted in dash-dot and dash-dash lines shown in FIGS. 3 and 6 show the area of the enlarged view and form no part of the claimed design.
